WITNESS:

UNITED STATES PATENT OFFICE

WILLARD A. MOORE AND KENNETH L. MOORE, OF MUNCIE, INDIANA

PIN

Application filed January 20, 1931. Serial No. 510,015.

This invention relates to guides or pins for assuring proper coincidence of the respective sections of a mold or flask whereby the pockets formed in each of the mold sections 5 will not become misaligned or staggered to cause the molded work to be formed with lips or projections upon the sides thereof.

Another of the objects of the invention consists of a pin and universal connection 10 between the sections of the mold or flask whereby adjustment may be afforded in all directions.

More specifically stated the pin supporting portion and joint supporting portions 15 of the guide are removably positioned upon the flask or mold in a manner whereby same may be removed and replaced without disturbing the mold or the molten metal while cooling.

With the above and other objects in view, the invention further consists of the following novel features and details of construction, to be hereinafter more fully described, illustrated in the accompanying 25 drawing and pointed out in the appended claim.

In the drawing:—

Figure 1 is a sectional view taken through the present invention as applied upon the 30 component sections of a mold or flask for aligning same in the manner stated.

Figure 2 is an end elevation of the invention.

Figure 3 is a top plan view of the invention.

Figure 4 is a horizontal sectional view taken through a form of adjustable seat for the universal joint.

Referring to the drawing in detail where- 40 in like characters of reference denote corresponding parts, the reference characters 10 and 11 indicate the component or complementary sections of a mold or flask; each of which is provided with flanges 12 out- 45 wardly projecting in parallelism from the sides thereof adjacent the meeting edges of the sections proper, substantially as illustrated in Figure 1 of the drawing.

All of the above is of the usual and well 50 known construction followed or otherwise

employed in the construction of molds or flasks of the character described and which forms no part of the present application for Letters Patent but are merely mentioned for purposes of illustration in bringing forward 55 the novel advantages of the present invention.

The invention primarily resides in the provision and arrangement of a plate member 13 to be hereinafter referred to as the 60 drag half, bifurcated as at 14, to accommodate the adjacent flange of the mold or flask section 10 to be hereinafter referred to as the flask drag. Set screws 15 and 16 are adjustably aligned within the opposite side walls of 65 the bifurcation 14 for biting engagement with the opposed surfaces of the immediate flange. A housing member 17, to be hereinafter referred to as the cope half, is also provided with a bifurcated portion 18 to accommodate 70 the flange of the mold or flask section 11 or otherwise identified as the flask cope. Set screws are also carried upon the opposite side walls of the bifurcation 18 to engage the immediate flange in the manner contemplated 75 for the drag half. A ball member 19, carried within the housing portion of the cope half 17, is adjustably seated therein by an annulus 20. Said ball member is furthermore drilled to provide a guide passage 21 80 for the accommodation and projection of a pin member 22 carried by the drag half 13.

A locking element, in the nature of a set screw 23, carried by the housing member or cope half 17 and which may be in the nature 85 of a set screw, projects for an appreciable distance therein for biting engagement with the surface of the annulus 20 thereby preventing accidental displacement.

The invention is susceptible of various 90 changes in its form, proportions and minor details of construction and the right is herein reserved to make such changes as properly fall within the scope of the appended claim.

Having described the invention, what is 95 claimed is:

A guiding and aligning apparatus for the drag and cope halves of mold sections comprising supporting members having means 100 for attachment to the mold sections, one of

said members having an internally threaded socket forming a housing, an annulus engaging the thread of the socket, a ball mounted for turning movement in the annulus and provided with a diametrically disposed opening, a pin received in the opening of the ball, said pin being mounted upon the other member and held against longitudinal movement thereon and means for fixing the ball with relation to the first mentioned member.

10 In testimony whereof we affix our signatures.

WILLARD A. MOORE.
KENNETH L. MOORE.
